(57) **CLAIM**

The ornamental design for an electroacoustic device as shown and described.

DESCRIPTION

FIG. 1 is a top perspective view of an electroacoustic device. FIG. 2 is a bottom perspective view of the electroacoustic device.

FIG. 3 is a front elevational view of the electroacoustic device.

FIG. 4 is a back elevational view of the electroacoustic device.

FIG. 5 is a right side elevational view of the electroacoustic device.

FIG. 6 is a left side elevational view of the electroacoustic device.

FIG. 7 is a top plan view of the electroacoustic device; and, FIG. 8 is a bottom plan view of the electroacoustic device. The electroacoustic device can be used, for example, as a component in an audio system, with a speaker and associated electronic components mounted in a drum.

The broken lines shown in FIGS. 1-8 are included for the purpose of illustrating environmental structure and form no part of the claim.

1 Claim, 8 Drawing Sheets
